6 Claims.

(Cl. 267—9)

This invention relates to spring units for use in spring assemblies for railway cars.

One of the objects of the invention is the provision of a new and improved spring unit having novel means for frictionally resisting the free movement of the unit during use.

A further object of the invention is the provision of a new and improved friction device for frictionally engaging the coils or turns of a helical spring during its movement under compression or release.

A further object of the invention is the provision of a new and improved friction device for use in connection with helical springs for dampening the vertical vibration of the same.

A still further object of the invention is the provision of a new and improved device for use on one or more helical springs of a spring assembly for railway cars that is simple in construction, inexpensive to construct, easily installed and that is effective in operation.

Other and further objects and advantages of the invention will appear from the following description taken in connection with the accompanying drawing in which—

Fig. 1 is a side elevation of a truck frame showing the invention in position thereon;

Fig. 2 is a vertical section through one of the units;

Fig. 3 is a perspective view of one of the friction devices;

Fig. 4 shows a modified form of construction;

Fig. 5 is a vertical section through one of the units showing a further modified form of construction;

Fig. 6 shows a perspective view of a modified form of the friction device; and

Fig. 7 is a view similar to Fig. 5 but showing a modified form of unit.

In load supporting spring assemblies for railway cars, wherein the conventional free acting helical springs are employed, it is not uncommon in use for these springs to develop harmonic action. There are various causes for such action.

Flat wheels, low places in the track occurring at regular intervals, rail joints, and the like, combined with critical speeds of the car, are some of these causes. For instance, if the conditions are such that the causes or sources of vertical vibration of the car synchronize with the natural vibration of the springs, the vibrations may build up to such a point that an accident may result as where the springs go solid and cause their breakage or breakage of the car truck parts.

The present invention seeks to dampen or

cushion this free movement by providing means for frictionally engaging the turns of the helical springs.

Referring now to the drawing, the reference character 10 designates a side frame of a railway truck having the bolster opening 11 therein for receiving the end 12 of the bolster. The bolster is supported by a spring assembly 13 which comprises a plurality of helical springs 14 and one or more spring units 15. The spring unit 15 comprises a helical spring 16 similar to the conventional helical spring 14 and interchangeable therewith and a friction device 18.

Suitable means are provided for frictionally engaging the intermediate turns 17 of the helical spring 16. In the form of the construction shown, which is by way of example only, a friction device 18 is employed for this purpose. This device comprises a plate or base 19 having upstanding spring arms 21 integral with, or rigidly secured to, the plate member 19. The inner or attaching portion 22 of the arms is bowed outwardly to give added resilience to the arms 21.

Any suitable number of arms 21 may be employed. In the form of the construction shown, three arms 120° apart are provided. These arms are of resilient material and have their outer ends bent outwardly as at 23 in order to function as guides when the spring 14 is inserted in position. The arms are so constructed that when the device is removed from the spring, they converge slightly toward their outer ends so that when they are in position on the spring 14, these arms will be parallel and will grip the turns of the spring for frictionally resisting the oscillation of the spring.

It will thus be seen that when the spring is compressed, the arms will frictionally engage the outer surfaces of the coils and since these coils, as the spring is compressed, tend to increase in diameter, these arms will more firmly grip the spring and consequently the frictional resistance to the compression of the spring by the arms 21 will increase as the unit is compressed. Likewise, there will be frictional resistance also to the expansion of the spring but since the helical spring contracts somewhat in diameter, this friction on release will be somewhat less than on compression. The arms are of such material and are so constructed that the frictional resistance will at no time be excessive so that when the spring is released, it will readily and promptly expand or assume its normal unexpanded position.

In Fig. 4 is shown a modified form of a spring unit. This form of construction differs from that

shown in Figs. 1 and 2 in that two of the friction devices 18 are employed, one at each end of the spring. The friction devices are turned relative to each other before they are placed in position so that the arms 21 will not interfere with each other during the spring movement.

In Figs. 5, 6 and 7 is shown a modified form of friction member and in this form of construction, the resilient arms are adapted to engage the inner surface of the spring instead of the outer surface thereof as in Figs. 1 to 3. In this form of construction, the base 24 extends radially outwardly beyond the arms 25 which are integral with, or rigidly attached to, the base 24. As shown, the base may be slit as at 26 and the tongue formed thereby bent upwardly to form a portion of the arm 25, see Fig. 6. The arms 25, however, may be secured to the base in any suitable manner, as by being integral therewith. The arms 25 have their lower or attaching portions 27 bowed inwardly to increase the resiliency of the arms and their outer ends are bent inwardly as at 28 to guide the same into the spring when the device is applied.

When in position within the spring 17, the outer coil of the spring 17 rests on, or engages, the base 24, and the arms 25 frictionally engage the inner surfaces of the spring. The arms are so constructed that they normally diverge outwardly when not in position within the spring 17 so that when they are inserted in the spring, they will be parallel and there will be sufficient pressure to create the necessary friction to prevent harmonic action of the spring and of the spring assembly.

A modified form of the construction is shown in Fig. 7. This differs from that shown in Fig. 5 in that one of the interior friction devices is employed at each end of the spring. These devices are duplicates and further description is believed to be unnecessary.

It will thus be seen that with either form of construction, the resilient arms will frictionally engage either the inner or outer surfaces, or both the inner and outer surfaces, of the intermediate coils or turns of the springs to frictionally resist the compression and expansion of those springs.

While the constructions described above are limited to the device being used on either the exterior or interior of the helicals, it is understood that where necessary or desirable, as where more sluggish movement of the helicals is required, both inner and an outer friction devices may be employed on the same helical.

It is thought from the foregoing, taken in connection with the accompanying drawing, that the construction and operation of my device will be apparent to those skilled in the art and that changes in size, shape and proportion may be made without departing from the spirit and scope of the appended claims.

I claim as my invention:

1. A spring unit comprising a friction member provided with a circular base plate forming a seat for said spring, said base plate having a solid central portion, a helical spring having one end directly engaging said base plate, a plurality of resilient arms integral with, and extending outwardly from, said base plate and frictionally engaging turns of said spring, said arms being provided with curves of short radius adjacent

said plate, the outer ends of said arms being normally a different distance apart than their inner portions whereby when the device is in position on said spring, the arms will be substantially parallel and each will frictionally engage a plurality of turns of said spring. 5

2. A spring unit comprising a railway car bolster supporting helical spring, a friction device on each end of said spring, each device comprising a base plate having a solid central portion 10 engaging one end of said spring, three spring arms equi-distant apart integral with said plate frictionally engaging the exterior of a plurality of turns of said spring, the inner portions of said arms being bowed outwardly to avoid engagement with the adjacent turns of the spring, the arms of said friction devices being spaced angularly and lapping past one another.

3. A spring unit comprising a railway bolster supporting helical spring, a friction member associated with said spring, said member comprising a circular base plate having a solid central portion engaging one end of said spring, a plurality of resilient arms integral with said plate and extending outwardly in planes at right angles 20 to said base plate, and frictionally engaging intermediate turns of said spring, each of said arms having a resilient portion bowed sharply outwardly adjacent to said base.

4. In combination, a spring unit comprising a 30 railway car bolster supporting helical spring, a friction unit having a circular base plate having a solid central portion on which said spring is seated, said plate being substantially of the same diameter as the external diameter of said spring, 35 resilient arms integral with, and extending upwardly from, said base plate and frictionally engaging the inner sides of intermediate turns of said spring, said arms normally being non-parallel whereby when in position on said spring 40 said arms will be resiliently forced into frictional contact with the turns of said spring.

5. A spring unit comprising a railway car bolster supporting helical spring, a plurality of dampener members associated with said spring, 45 one of said members comprising a base plate having a solid central portion, a plurality of resilient arms rigidly connected to said base plate and extending into and frictionally engaging the inner sides of the intermediate turns of 50 said spring, the other member comprising a base plate, a plurality of resilient arms rigidly connected to said base plate and frictionally engaging the outer surfaces of the intermediate turns of said spring.

6. For use with a helical spring, a friction member comprising a base plate of sufficient breadth to form a firm three-point support for an end convolution of the spring, at least three resilient arms rising from the plate for frictionally engaging a plurality of convolutions of the spring, the outer spring engaging ends of said arms being normally spaced apart a different distance than the inner spring engaging portions thereof whereby when the device is in position on the spring the arms will be substantially parallel and each will frictionally engage a plurality of convolutions of the spring, the inner ends of each of the arms being directly joined to the adjacent arm by a solid portion 65 of the base plate.

CYRUS J. HOLLAND.
